(57) **CLAIM**

The ornamental design for a pet dryer, as shown and
described.

DESCRIPTION

FIG. 1 is a perspective view of the pet dryer, showing the
present design.

FIG. 2 is a front view thereof.

FIG. 3 is a rear view thereof.

FIG. 4 is a left side view thereof.

FIG. 5 is a right side view thereof.

FIG. 6 is a top view of thereof; and,

FIG. 7 is a bottom view of thereof.

The broken lines illustrate portions of the pet dryer that form
no part of the claimed design.
